UNITED STATES PATENT OFFICE.

JAMES A. McCREARY, OF CONNELLSVILLE, PENNSYLVANIA.

COKE-OVEN DOOR.

1,200,123.

Specification of Letters Patent.

Patented Oct. 3, 1916.

Application filed November 15, 1915. Serial No. 61,716.

To all whom it may concern:

Be it known that I, JAMES A. McCREARY, a citizen of the United States, residing at Connellsville, in the county of Fayette and 5 State of Pennsylvania, have invented certain new and useful Improvements in Coke-Oven Doors, of which the following is a specification.

This invention relates to a novel improvement in doors of the character that are especially adapted for use in connection with coke ovens.

Primarily the present invention contemplates a coke oven door of the type having 15 upper and lower door sections which may be handled separately or as a unit, and which departs from the usual skeleton-like framework common to doors of this character by providing each section with an imperforate back. In this connection, the invention also proposes to provide an air space between the rear side of the usual tile filling exposed to the heat of the coking chamber and the imperforate metal back, so that heat 20 will not be directly conducted thereto but will be lessened by the intervening air gap.

A further object of the invention is to provide a rigid and substantial frame construction for each door section whereby the 30 tiles will be detachably and adjustably locked in place, while at the same time providing a novel frame construction whereby the joint between the doors may be sealed and each section securely held to the other 35 to permit of the doors being handled as a unit when desired.

With the above and other objects in view which will more readily appear as the nature of the invention is better understood, 40 the same consists in the novel construction, combination and arrangement of parts, hereinafter more fully described, illustrated and claimed.

A preferred and practical embodiment of 45 the invention is shown in the accompanying drawings, in which—

Figure 1 is an elevation of the outer side of the present coke oven door, showing the tile filling and tile-engaging and spacing 50 means in dotted lines. Fig. 2 is a vertical sectional view on the line 2—2 of Fig. 1. Fig. 3 is a horizontal sectional view on the line 3—3 of Fig. 1. Fig. 4 is a composite view showing the removable and replaceable 55 tile units in elevation without the frame, and also showing projected side and bottom

edge views thereof. Fig. 5 is an enlarged detail sectional view of the joint between the doors, and also shows the means for locking the door sections together more clearly. Fig. 6 is a detail sectional view on the line 6—6 of Fig. 5.

Similar reference characters designate corresponding parts throughout the several figures of the drawings.

By reference to the accompanying drawings, it will be observed that the door forming the subject of the present invention essentially comprises a lower door section 1, and an upper door section 2 having therein 70 an opening 3 for receiving the hook of a trolley device (not shown). This device, however, is well known in the handling of coke oven doors, and is utilized to lift the upper section from the lower section when 75 desired to shift the upper section away from the oven door, or handle the entire door as a unit when the upper and lower sections thereof are locked together. The opening 3 referred to is preferably closed by a pivoted 80 shutter 4, so that the door may be made air tight during the coking operation.

The said lower door section 1 essentially includes an imperforate sheet metal back 5 which has secured upon its inner face the 85 oppositely located vertically arranged tile-engaging bars 6. These bars are preferably spaced from the side edges of said door section to leave projecting cover flange portions 7 which overlap the sides of the oven 90 doorway to hold the door in its closed position, and also assist in forming an air tight joint. The said bars 6 are secured to the back 5 by means of the rivets or bolts 8, and are each provided with an angular tile engaging flange 9 which is preferably disposed at such a distance from the back 5 that the tile or tiles engaged thereby are also spaced therefrom.

The lower edge portion of the door section 1 has fitted to its inner side a horizontally arranged adjustable tile supporting and locking bar (see Fig. 2) which has formed at one edge thereof an angular tile engaging flange 11. The said bar 10 is adjustably secured to the inner face of the back 5 by means of the bolts 12 mounted in the slots 13 of said back, and works in opposition to the fixed abutment bar 14 at the inner side of the top edge portion of the 105 back 5. In connection with the abutment bar 14, it will be observed that the same is 110

arranged horizontally of the lower door section 1, and projects above the extreme upper edge thereof (see Fig. 5) to provide a rabbet or recess 15, and is rigidly secured in place 5 by means of suitable bolts or rivets 16.

At the opposite upper corners of the lower door section, the back 5 is provided upon its outer side with retaining plate members 17 which coöperate with the portion of the 10 abutment bar 14 projecting above the upper edge of the solid metal back to provide a keeper groove 18, the purpose of which will hereinafter more fully appear. With further reference to the bar 14, it will be observed 15 that the same, like the other tile retaining members 6 and 10, is provided with an angular tile engaging flange 20 which extends throughout the length of the bar, and is adapted to engage the upper sides of all of 20 the tile units held within the lower door section.

The upper door section 2 is similar in construction to the lower section 1, and includes an imperforate metal back member 21 having at its upper edge portion an arched vertically adjustable tile locking bar 22, which is mounted on the inner face of the back 21 by means of the bolts 23 fitted in the slots 24 in the back. Through the adjustment 25 provided by the slots 24 the locking bar 22 works in opposition to a fixed abutment bar 25 at the inner side of the lower edge portion of the back 21. The said abutment bar 25 serves as a rigid and fixed support 30 for the tile filling of the upper door section, and engages the tiles thereof by means of the angular edge 26, while the upper edges of the tiles clamped between the bar 25 and the bar 22 are engaged by the angular flange 35 27 on the bar 22. By reference to Figs. 2 and 5, it will be observed that the abutment bar 25 is secured to the inner face of the back 21 by means of suitable fastening elements 28, and is also spaced above 40 the extreme lower edge of the back 21 to have a downwardly projecting sealing flange 29.

The abutment bar 25 above referred to is preferably provided with spaced slots 50 30 which are adapted to receive the keeper straps 31 carried by the lower door section. These straps project through and above the abutment bar 14 of said lower section, as more clearly shown 55 by Fig. 5, and also project above and interlock with the abutment bar 25 of the upper door section, thereby preventing relative longitudinal and lateral movement 60 between the two door members when they are connected and in use. The upper ends of the straps 31 are formed with a circular keeper opening 32, adapted to receive the flat cam end 33 of a locking pin 34 loosely inserted in the opening 35 in the lower edge of 65 the upper door section 2, and which cam 33 is

eccentric to the circular keeper opening 32 of the strap. The locking pins 34 are preferably provided with an angular handle portion 36 which may be manipulated from the outer side of the door, so that the flat cam end 33 of the pin may be forced into positive engagement with the strap 31 within the keeper opening 32 thereof. Ordinarily the pins 34 are inserted in the upper door section 2 so that the cam end 33 occupies the position shown in full lines in Fig. 6, and as the handle 36 of the pin is forcibly turned, one of the side edges of the cam portion 33 binds or impinges against the side of the keeper opening 32, while the other side edge binds against the top of the bar 25 as shown by dotted lines in this same figure. In this way, the abutment bars 14 and 25 may be securely clamped together.

The tile filling for the present door is 85 designated generally as T, and is shown in detail independent of the door in Fig. 4. From this figure it will be apparent that the tile units 37, 38 and 39 are provided with curved or arched top portions to fit the adjustable locking bar 22 of the upper door section, while the tile units 40, 41 and 42 of the lower door section are preferably of rectangular formation. The edges 43 of all the tile sections which abut with each 90 other are preferably flat, while the other edges which engage with metal parts of the door are provided with an offset metal protecting face 44, and the flange receiving grooves 45. Accordingly it will be apparent 95 that the tile units are engaged by the angular flanges on the edges of the adjustable bars 10 and 22, fixed abutment bars 14 and 25, and vertical bars 6, and since the tile engaging flanges of each of these bars 100 are purposely spaced a desired distance from the inner face of the backs of the door, the tiles when in assembled position on the door will be spaced from the backs 21 and 5 to provide air insulating spaces A and B. 105 The tiles 37 and 40, and 39 and 42 are provided with complemental recessed portions 46 and 47 which provide sufficient clearance 110 for the devices that detachably lock the two door sections together.

With reference to the placing of the tiles within the door sections, it will be noted that the upper tile units 37, 38 and 39 are clamped in position by means of the adjustable bar 22 working in opposition to the fixed bar 25. In the lower door section 1, the tiles 40, 41 and 42 are clamped in position through the medium of the adjustable locking bar 10 working in opposition to the fixed abutment bar 14, and in this 115 instance the tiles are also held in position by means of the oppositely located vertically arranged tile retaining bars 6.

From the foregoing description it will 120 be apparent that each of the door sections 130

include a tile filling spaced from the solid metal back members of the sections to form an insulating air space, while the two sections meet at the abutment bars 14 and 25.

5 Owing to the particular construction and arrangement of the said bars 14 and 25 whereby the upper door section is provided with a rabbeted portion or keeper groove 18, it will be apparent that the joint formed 10 between the meeting faces of the abutment bars 14 and 25 is located behind the sealing flange 29. This flange therefore, prevents air from entering at this point and forms a most effective joint, while the presence of 15 the locking pins 34 working in conjunction with the keeper straps 31 not only increases this effectiveness, so that a tight joint may be maintained through the coking operation, but also makes it possible to easily 20 break the connection between the door members when desired.

When the locking pins 34 are in position, and the upper and lower door sections locked together, it will be apparent that 25 the door may be handled as a single unit to be removed from the oven doorway as for instance, during the watering operation. However, should it be desired to remove the upper section only, as when leveling the 30 coal contents of the oven before coking, it is necessary to withdraw or extract the pins 34 so that the ends 33 thereof become free from the straps 31. To facilitate the handling of the upper door section independently of the lower door section, the same is provided with a suitable lever retaining hook 48 for engaging the lever device of the trolley mechanism usually employed in connection with coke ovens, to thus hold the 40 door in a lifted or raised position.

When the door sections are held together in their operative position, it will be apparent that the same cannot move longitudinally or laterally on account of the keeper 45 straps 31 engaging with the bar 25, and it will also be apparent that the backs 5 and 21 of the sections are held in proper alignment by means of the opposite ends of the sealing flange 29 engaging in the keeper 50 grooves 18 formed by the retaining plates at the opposite upper corners of the lower door section. As the door in this form presents a solid back, and an effective joint where the two sections meet, it will be apparent 55 that no air can enter the oven through the door itself, and could only enter at the edges. However, air is prevented from entering the oven at this point by means of the customary filling of loam or other plastic material being placed in the well known manner.

From the foregoing it is thought that the many features and advantages of the present invention will be apparent without 60 further description, and it will be readily

understood that minor changes in the form, proportion and details of construction may be resorted to without departing from the spirit of the invention or scope of the appended claims.

70

I claim:

1. A coke oven door including upper and lower door sections, each section including an imperforate metal back, fixed tile engaging and spacing means, adjustable tile locking means working in opposition to said fixed means, means for forming a sealed joint between the abutting fixed tile engaging means, and means for detachably locking said door sections together.

75

2. A coke oven door including upper and lower door sections each having a fixed abutment bar arranged in abutting relation, means for forming a sealed joint between said fixed bars, and means for detachably locking said door sections together.

80

3. A coke oven door including an upper door section having a fixed abutment member, a lower door section also having a fixed abutment member adapted to contact with the fixed member of the other section, keeper means carried by one of said door sections, and means for detachably engaging the other of said door sections and the keeper means carried by said first mentioned section.

90

4. A coke oven door comprising detachably connected door sections, each section including an imperforate metal back having a fixed tile engaging and spacing member for abutting with the corresponding member of the other, each section also including an adjustable tile locking and spacing member working in opposition to said fixed member, means carried by one of the door sections for forming a sealed joint between the meeting edges of the abutting members, and means for detachably locking said sections together.

100

5. A coke oven door including an upper door section having a fixed abutment bar at its lower side, a sealing flange projecting below said abutment bar, a lower door section having a fixed abutment bar at its upper side and having formed at one edge thereof a recess for receiving said sealing flange, and means for detachably connecting said sections together.

110

6. A coke oven door including an upper door section having a fixed abutment bar, a lower door section also having a fixed abutment bar adapted to flushly contact with the bar of the other section, keeper members carried by said lower door section, and removable locking pins for detachably engaging said upper door section and said keeper members.

120

7. A coke oven door including an upper door section having a tile filling spaced therefrom, a fixed tile supporting bar pro-

130

vided with spaced slots arranged adjacent the lower edge of said section, and a lower door section also having a tile filling spaced therefrom, a fixed abutment and tile engaging bar carried by said lower door section and adapted to flushly abut with said fixed tile supporting bar, spaced keeper members carried by said abutment and tile engaging bar and adapted to enter the openings in the tile supporting bar of the upper section, and removable locking pins for engaging said upper door section and said keeper members.

8. A coke oven door comprising detachably connected door sections, each section including a back member having adjustment slots, a fixed tile supporting bar carried by said back and having a tile engaging flange spaced therefrom, an adjustable tile locking bar also carried by said back and having a tile engaging flange spaced therefrom, said adjustable bar carrying fastening elements working in said adjustment slots in the back, a tile filling carried by said bars and spaced from the back, and means for detachably connecting said sections.

9. A coke oven door including an upper door section having an imperforate metal back, a tile filling spaced therefrom, and a lower section having an imperforate metal back, opposite vertically arranged side bars carried by said back, an upper rigid abutment and tile engaging bar, a lower ad-

justable tile supporting bar, a tile filling spaced from said back and held between the side bars and clamped by the locking bar against the rigid bar, and means for detachably connecting said door sections together.

10. A coke oven door including an upper door section comprising a sheet metal back, a fixed tile supporting member arranged adjacent the lower edge thereof, a sealing flange projecting below the fixed tile supporting member, and an adjustable tile supporting member working in opposition to said fixed member, a lower door section also providing a sheet metal back, a fixed tile engaging member arranged above the upper edge thereof and adapted to flushly abut with the fixed tile supporting member of the upper section to form a joint behind the said sealing flange, retaining plates carried at the upper corners of the back of said lower section and providing keeper grooves for said sealing flange, an adjustable tile supporting member working in opposition to said fixed tile engaging member, and means for detachably locking said door sections together.

In testimony whereof I hereunto affix my signature in the presence of two witnesses.

JAMES A. McCREARY.
